UNITED STATES PATENT OFFICE.

WILLIAM JOHN BLAIR, OF MELBOURNE, VICTORIA, AUSTRALIA, ASSIGNOR TO ALEXANDER EATON WOODS, OF MELBOURNE, AUSTRALIA.

MEANS FOR AUTOMATICALLY RECORDING CALLS IN TELEPHONE SYSTEMS.

1,382,817.

Specification of Letters Patent. Patented June 28, 1921.

Application filed April 28, 1917. Serial No. 165,163.

To all whom it may concern:

Be it known that I, WILLIAM JOHN BLAIR, a subject of the King of Great Britain, residing at 376 William street, Melbourne, Victoria, Australia, have invented certain new and useful Improvements in Improved Means for Automatically Recording Calls in Telephone Systems, of which the following is a specification.

10 This invention refers to telephone systems and consists of additional devices and slight variations in the circuits at the control exchange for the purpose of enabling effectual or both effectual and ineffectual calls to be 15 automatically recorded.

Briefly stated one, or a set of relays, inserted in the circuit of the answering and calling plugs at the exchange, controls contacts in the circuits of the effectual and ineffectual call meters and operate by de-energization to momentarily complete one or other of the registering circuits.

In a simple form of the invention the control relay or relays are arranged to operate only the effectual call meter.

The improvements include means controlled by the relay for setting the contacts in the registering circuits ready to momentarily complete the latter and subsequently 30 to re-set the contact or contacts while in addition means are provided for preventing a calling subscriber's meter registering when exchange in error connects with the wrong subscriber.

35 The invention is applicable to systems provided with a common battery and to systems in which an exchange having a common battery is connected to a sub-exchange having a magneto system.

40 The invention is illustrated by the accompanying drawings whereof—

Figure 1 is a diagrammatic plan of the common battery system showing the exchange circuits and the circuits of the calling subscriber's telephone.

45 Fig. 2 is an enlarged detail of the meter relay control contact.

Fig. 3 is a diagram of the circuits for automatically recording both effectual and ineffectual calls; and

Fig. 4 is a detail of the relay control contact;

Fig. 5 is a diagram of the circuits between a common battery exchange and a magneto 55 sub-exchange;

Fig. 6 is a similar view to Fig. 3 illustrating another arrangement of relays;

Fig. 7 illustrates a special relay for actuating both the effectual and ineffectual meters;

Fig. 8 is an underside plan of the armatures beneath the relay shown in Fig. 7;

Fig. 9 is a section on line IX—IX Fig. 8;

Fig. 10 is an illustration of a simple form of control relay;

Fig. 11 being an underside plan; and

Fig. 12 an end elevation;

Fig. 13 is a side and Fig. 14 a front elevation of a relay operating the same as that shown in Figs. 10-12; and

Fig. 15 is a top view of Fig. 13;

Figs. 16 to 18 illustrate the simplest form of the invention, Fig. 16 being a diagrammatic plan of the common battery system 75 showing the exchange circuits and the circuits of the calling subscriber's telephone and containing the essential elements of these improvements;

Fig. 17 is an enlarged diagrammatic view 80 of the control relay and related parts showing said relay set to register an effectual call; while

Fig. 18 is a top view of said control relay.

In the drawings it will be noted that 85 where a relay operates two armatures the latter are shown for convenience at the respective ends of the relays.

Furthermore the approximate relative resistances are expressed in figures on the 90 drawings.

Referring to Fig. 1 it will be seen that an additional relay X is provided which is connected by the line 4 with the battery 32 and the line 5 with a contact 6 made by the armature 7 of the calling plug supervisory relay 8. Line 4 is connected by line 9 making contact 10 with an armature 11 operated by the relay X and said armature is in the circuit of the supervisory lamp 12.

A short circuit line 13 connects with line 5 and joins with armature 11 when relay X is energized. Relay X has another armature 14 connected by line 15 with the effectual meter circuit, said armature being adapted when relay X is deenergized to make the control contact 16 of the call recorder circuit of the exchange and subscribers effectual call meters 17, 18.

The armature 14, (Fig. 2) is normally be-

neath and insulated from an armature 19 of a low resistance relay 20 and rests against a stop 21 and when relay X is energized armature 14 moves from under armature 19 which drops on the stop 21 and the contact is thus set so that when relay X is de-energized armature 14 will fall against the end of armature 19 and make contact 16.

Relay 20 is connected by line 22 to an 10 additional armature 23 of the answering plug supervisory relay 24 and said armature 23 normally contacts at 25 with line 26 leading to the sleeve of answering plug of calling subscriber A.

15 Assuming A to be calling B, when A takes his receiver off the hook 27 he closes a circuit through his telephone with battery 28 thus causing line lamp 29 to glow until the operator inserts answering plug 30 into A's 20 local jack 31 when current will flow from battery 32 through supervisory lamp 33, sleeve of plug 30, ring 34 of jack to cut out relay 35 thus cutting out the battery 28 and extinguishing the line lamp 29. Also relay

25 24 becomes energized and its right end armature 36 shunts the lamp on account of its resistance being much greater than that in line 37 leading to the armature 36 so that the lamp is extinguished and furthermore 30 the armature 23 being attracted to relay 24 the call recording circuit 22-25 is broken.

B's number being given the operator then inserts calling plug 38 into B's multiple jack 39 and rings. In the meantime current 35 from battery 32 is flowing through lamp 12 to sleeve 40 and ring of jack 39 to the cut out relay (as above described but not repeated in the drawings) causing lamp 12 to glow.

40 When B takes off his receiver he closes the circuit with battery 32 thus energizing relay 8 whose armature 7 makes contact 6 closing the circuit through line 4, relay X and line 5. Relay X attracts both armatures 11, 45 and 14 the former shunting the lamp 12, which becomes extinguished, and the latter setting the control contact of the circuit of the meter (Fig. 2).

It is to be noted that armature 63 is not, 50 under the system being described, attracted—the operation of such armature being described hereinafter.

When conversation is finished A and B hang up their receivers, whereupon relay 8 55 is deenergized and armature 7 falls and breaks contact 6, but current still flows through relay X by way of line 13, armature 11, lamp 12 to sleeve 40 thus causing said lamp 12 to glow indicating that B has 60 hung up his receiver.

Similarly relay 24 is deenergized and lamp 33 glows and contact 25 is made so that the meter circuit is only broken by control armature 14 at relay X.

65 The operator now extracts calling plug 38

from B's multiple jack 39 thus breaking the circuit of relay X and allowing the armature 14 to fall against armature 19 (Fig. 2) making momentary contact 16, whereupon current from meter battery 44 operates exchange meter 17 and current also flows through line 22 armature 23, line 26, sleeve of answering plug 30, line jack 31, line 45 and also operates subscriber's meter 18.

The energization of relay 20 immediately 75 attracts and lifts armature 19 thus breaking contact 16 whereupon armature 14 of relay X falls against stop 21 and the recording circuit being then broken armature 19 falls on the insulated end of armature 14.

80 Should subscriber A be unable to raise subscriber B relay X is not operated as supervisory relay 8 is not energized and in consequence armature 14 is not set for the meter control circuit, but upon the operator removing the calling plug 38 she may register an ineffectual call on the ineffectual meter 46 by operating key 47 in the usual manner.

In the case where the operator calls an incorrect number and the called subscriber answers then the control contact is set to register a call, but when the calling subscriber A ascertains the mistake the operator's attention is called to the fact. Upon calling 95 plug being extracted to be correctly placed, no call is registered on the meters, because the meter circuit is broken at contact 25 for the reason that relay 24 is energized and is attracting armature 23 while A's receiver is 100 off the hook.

By a slight modification of the arrangement described and the circuits as illustrated in Fig. 1 the ineffectual calls may also be 105 automatically registered.

In this case the exchange effectual call meter is connected with armature 23 by line 22 (see Fig. 3) without interruption and the armature 14 of relay X becomes a two-way switch, of the gravity type for instance, and 110 is adapted to make one or the other of two contacts 48, 49, the former 48 in the circuit 70 of a low resistance relay 50 and of the effective call meter 17 which line has a branch 71 leading to a high resistance 72. 115 The other contact 49 is in the circuit of the ineffectual call meter 46, and the armature 14 normally rests against such contact.

The line from battery 32 is connected with another extra relay 51 connected with relay 120 X and operating a relay contact 52 (Fig. 4) similar to that shown in Fig. 2.

According to this arrangement when an ineffectual call has been made the withdrawal of the calling plug makes control 125 contact 52 and current from battery 44 passes along through armature 14 and contact 49 and operates the magnet of ineffectual call meter 46.

If the correct subscriber is raised relay 8 is 130

- energized, shunting lamp 12 and making contact at armature 7 thus sending current through relay X which attracts armature 14 and makes contact 48 ready until the subscribers' receivers are hung up and the calling plug extracted when control contact 52 is made and current momentarily flows from battery 44 through contacts 52, 48 line 70 passing through low resistance relay 50 except 5 change effectual meter relay 17, line 22, sleeve of answering plug, line jack 31 line 45 to the magnet of subscriber's meter 18 thus recording an effectual call against the subscriber and adding a call to the exchange operator's record. This current in passing through the low resistance relay 50 momentarily attracts armature 14 which subsequently rests by gravity against the contact 49.
- 20 In the case where the subscriber A wishes to raise B and the operator calls subscriber C in error and the latter subscriber answers relay X is energized and contact 48 made and the control contact 52 set, but when the operator discovers the mistake and extracts the calling plug, control contact 52 is made and current from battery 44 passes along through contacts 52, 48 line 70 relay 50 through resistance 72 to earth as the contact 23 is broken by reason of subscriber A's receiver being still off the hook. No call is therefore recorded, but relay 50 being energized again attracts armature 14 which again rests against contact 49.
- 35 It will be noted that in each case above described after contact 52 has been made the relay 53 controlling same is instantly deenergized and the register circuits broken.
- Referring to Fig. 5 diagrammatically illustrating the arrangement and circuits between a common battery exchange and a connected magneto sub-exchange it will be seen that a resistance 54, as, for instance, 40 ohms, is inserted in the signaling circuit of the magneto jack 55 which resistance in conjunction with that in the cord circuit is sufficient to prevent relay X from operating when the magneto exchange operates the relay 8 and if the called subscriber does not answer nothing takes place.
- It may here be noted that in the system shown in Fig. 3 where the common battery exchange is connected with a magneto sub-exchange, as in Fig. 5, should the called subscriber not answer an ineffectual call would be recorded. Reverting to Figs. 5 and 6, should the called subscriber answer supervisory lamp 60 glows and a circuit is closed through relay 61 thus making contact at 40 armature 62 with armature 66 of relay 67 sending a strong current from battery 68 over common battery talking wires 175, 176 and putting extra energy into relay 8 thus operating armature 63 (used only in connection with a magneto exchange) and cut-

ting out resistance 64 when relay X will operate to set relay control contact 16 as before described, ready to record the call when subscribers have finished.

Fig. 6 illustrates the system shown in Fig. 70 with variations in the relays to accomplish the same result.

It will be seen that there are four relays added to the relay 8 on the calling plug side 271 and 272 being in one set and 73 and 74 in another, the former being for recording ineffectual calls and the latter 73 and 74 for recording effectual calls. Relays 272 and 74 are of 83.5 ohms resistance and are in the circuit of the supervisory lamp 12 while relays 271 and 73 are employed for re-setting control contacts in the respective registering circuits.

The method of operating is as follows:

When the calling plug 38 is inserted, current flows through relay 272, top spring 75 of relay 74 to center spring 76 to lamp 12 and sleeve 40 thus attracting armature 77 pulling spring 78 over clear of armature and lever 79 when the latter drops into the position shown. The first pair of relays 271 and 272 are now set ready to register an ineffectual call. If the subscriber does not answer and the operator extracts the calling plug, relay 272 is deenergized. When armature 77 and spring 78 fall back said spring comes in contact with lever 79 so that current flows from battery 44 to lever 79, spring 78 thence by the spring contact 87 of set Z² below relay 74 to ineffectual meter 46. In the event of the subscriber answering, in which case his lamp is shunted, current then flows from battery 32 through the line 81, relay 74 thence through resistance 40 ohms and thence through the solenoid 8, completing the circuit through the plug 38. This operates armature 82 and spring 83 and lets lever 84 drop ready to register on effectual meter 17. At the same time armature 85 is operated and cuts out the connections between top 75 and center spring 76 by forcing down said center spring and making contact with the bottom one 86 thus allowing relay 74 to remain energized after the shunt has been cut out when lamp 12 glows showing clearance. At the same time the bottom spring 87 is pressed down thereby breaking the register line to ineffectual meter 46. Thus when relay 272 becomes deenergized by relay 74 breaking circuit of battery 32 at springs 75 and 76, armature 77 and spring 78 fall away but cannot register on account of the broken line at set of springs at relay 74 so that when armature 77 follows spring 78 and makes contact current flows through lever 79, armature 77 to relay 271 on to earth, energizing relay 271 causing armature of relay 271 to raise lever 79 allowing armature 77 and spring 78 to fall under insulation at end of lever 79 without registering,

115
120
125
130

thus re-setting set Z^1 , leaving set Z^2 set to register on effectual meter 17 which is done by extracting calling plug 38 thus deenergizing relay 74 when armature 82 and spring 83 fall away said spring making contact with lever 84 when current flows from battery 44 over line 89 to 84 thence to 83 on to effectual meter 17 on to relay 24 to subscriber's meter 18 as described with reference 10 to Fig. 3. When armature 82 makes contact with 84 current flows through relay 73 and raises lever 84 thus re-setting apparatus again.

In lieu of the arrangement of relays described herein and used for registering effectual and ineffectual calls, the relay illustrated in Figs. 7-9 may be employed.

This relay 100 is differentially wound the inner winding is connected with battery 44 20 thence from winding through line 101 to armature 91 while the outside winding is from battery 32 through relay (83.5 ohms) to supervisory lamp 12 and shunt. There are four polarized armatures forming 2 sets 25 of armatures. 91 and 92 form one set and armatures 93 and 94 form the second or differentiating set.

The armatures 92 and 94 are so arranged that it requires greater strength of current 30 in the relay to lift armature 94 than is necessary to lift armature 92. This might be accomplished by the arrangement, angular set or weight of the armatures or by the use of springs. According to the means illustrated 35 the armature lies normally farther from the influence of the relay than the armature 92.

In connection with armature 94 there is a contact 95 bearing against its lower surface which is connected with the ineffectual meter 40 46 while armature 93 is connected with the effectual meter 17. The operation with this relay is as follows:—

Upon calling plug being inserted the nearer armature 92 is attracted and supervisory lamp 12 glows but armature 94 is not attracted as it is set a little too far away for the magnet to operate it with so much resistance as the lamp adds in circuit. Now upon 45 92 being attracted 91 is also attracted and falls in behind 92, but does not contact, but if subscriber does not answer and calling plug 38 is extracted relay 100 is deenergized 92 falls against hook of 91 making contact when current flows through from 30 volt 50 battery 44 to contact 95 to ineffectual meter 46. The current passing through first winding of relay 100 sets up an adverse influence and repels armature 91 allowing armature 92 to re-set itself.

Now should the subscriber answer, he operates the shunt thus causing 80 ohms difference in the circuit passing through relay 100 which will be more than enough to operate armature 94 which is attracted when 55 armature 93 falls in behind, also contact 95

is disconnected. Upon extraction of the plug the same operation as described takes place, but current flows from 91 to 92 through bridging spring 96 to 94 on to 93 to effectual meter 17 the reverse influence again re-setting the different parts of the combination. 70

It will be understood that the current from the 24 volt battery 32 sets up, say, a positive pole and by reverse winding the current from the 30 volt battery 44 sets up a negative pole 75 and the 80 ohms difference between an ineffectual call and an effectual call and the different adjustment of the two armatures 92 and 94 will readily lend itself to either leave the connection on the contact 95 of 80 ineffectual meter 46 or shift it to catch of armature 93 of effectual meter.

The control relay just described may be further simplified and provided with a simple winding and such construction is 85 illustrated in Figs. 10, 11 and 12 of the drawings.

In this control relay the inner winding shown in Fig. 7 is dispensed with and the armature 91 is connected by line 201 direct 90 to battery 244. The armature 292 is not used to make contact with armature 91 but instead a spring 103 supported by a strap 105 from said armature 292 is used said spring being connected by bridge piece 96^a 95 with armature 294. Instead of spring 95 as in Fig. 7 an arm 106 provided with an adjustable screw contact 106^a is employed said contact being broken when relay is set to register an effectual call. 100

In order to break contact 103 with the hook end of armature 291 immediately after being made, armature 291 is inclined at the lower end as at 104 and when armature 292, following the spring 103 contacts with the inclined part 104 it moves armature 291 from beneath the end of said spring 103 which latter can then only contact with the insulated end of armature 291. 105

As an alternative the members 291 and 293 110 need not be armatures but mechanically operating pendulum or spring contact arms having means such as a guide stud 109 to limit the swing of said members. The member 291 carries an insulated arm 108 which 115 extending behind member 293 frees the latter when said member 291 is repelled.

In Figs. 13-15 is shown a somewhat similar construction of relay used according to this invention. In this form the pivoted 120 hooked contact arms 120, 121 are arranged at the top of the relay and the armatures 122, 123 at the front, all being of the gravity type. The armatures are electrically connected at their lower or pivotal seatings 124 125 and are guided in their movements by guide studs 125, 126 the latter limiting their outward movement. As previously described one armature 123 is arranged so that it requires a greater current to lift it than the 130

other armature 122. The upper pivoted contact arms have hooks 127, 128 and the former has a bevel 129 and an inclined insulated projection 130 terminating at its 5 inner or hook end with a metal contact 131, said projection being lifted by the spring 132 supported by the strap 133 from armature 122.

The contact arm 121 has a finger 134 which 10 projects over the contact arm 120 which is insulated as at 135 beneath said finger. Contact 136 in the ineffectual meter circuit is normally made with armature 123 but is broken when relay is set to register an effectual call. 15 When one subscriber calls another, and the exchange operator inserts the plug, armature 122 is attracted, spring 132 engaging projection 130 lifts contact arm 120 and falls into hook opening as shown in dotted lines Fig. 13 and if the called subscriber does not answer, the plug is removed and armature 122 falls causing spring 132 to contact with contact 131 and so operates the magnet of ineffectual call meter 46 which latter registers. 20 Armature 122 following, engages bevel 129 and lifts contact arm 120 freeing the spring 132 and breaking contact of this registering circuit. 25 Armature 122 following, engages bevel 129 and lifts contact arm 120 freeing the spring 132 and breaking contact of this registering circuit.

Should the subscriber answer, the relay is 30 set as just described but in addition armature 123 is attracted, as the resistance is reduced, thus breaking contact 136 and engaging hook 128 of contact arm 121 as indicated in dotted lines Fig. 13. Subsequently upon 35 removal of the plug, armature 122 falls and in so doing engages bevel 129 and lifts contact arm 120 which through finger 134 also lifts contact arm 121 thus breaking contact at 127 and 128 and all parts of relay resume 40 normal positions as in Fig. 13.

The embodiment of the invention shown in Figs. 16-18 of the drawings is the simplest and most effective construction of this invention and therein it will be seen that the 45 relay X^1 has two armatures 171, 172 and two springs 173-174 all being mounted on an insulation block 175 and thereby electrically disassociated. Said armatures have rigid straps 181 which embrace the respective springs, and they are so arranged that it requires greater energy in the relay to lift armature 172 than is necessary to lift armature 171. This may be accomplished by the arrangement, angular set or weight 50 of the armatures or by the use of springs. It is, however, found to work satisfactorily by setting armature 172 somewhat farther back than armature 171 or farther from the magnetic influence of the relay. 55 At the top of the relay there are two hooks 177, 178 pivoted at their inner ends on an insulation block 176, the shanks of the hooks being inclined downwardly as at 179 and formed with insulated extremities 60 180. Suitable means are provided for lift-

ing hook 177 when armature 172 is attracted. One convenient means consists of a lifting arm 184 attached to the shank of hook 177 and bent so that its outer end overlies armature 172, the end of said arm being 70 formed with a bevel 183. This arm insures the circuit of the ineffectual call meter being broken when the contact controlling the effectual call meter circuit is set to be subsequently made. 75

The hook 177 is connected by line 185 with the relay of the ineffectual call meter 46 while the corresponding spring 173 leads to earth.

The hook 178 is connected by line 186 with the relay of the effectual call meter 17 while the corresponding spring 174 is in line 187 leading to additional contact 25 of the answering plug supervisory relay 24 whence a line leads to sleeve 30 of said plug, thence 80 by jack to relay 18 of subscriber's effectual call meter. The relay X^1 is connected as before described with battery 32 and calling plug supervisory lamp 12 and shunt 6. 90

According to the foregoing construction when a subscriber calls another, the exchange operator inserts the calling plug, armature 171 is attracted and holds spring 173 clear in front of hook 177, which latter 95 drops slightly. Should the called subscriber not answer, the plug is removed and relay X^1 is deenergized and armature 171 drops making spring 173 contact with hook 177 so that current from battery 44 flows through 100 the magnet of ineffectual call meter 46, line 185, hook 177, spring 173 to earth, thus registering an ineffectual call.

Should the subscriber answer and the supervisory lamp 12 be shunted and thereby effect reduction of resistance in relay X^1 the stronger current now passing through said relay attracts armature 172 as well as 171 and in rising armature 172 engages bevel 183 of lifting arm 184 causing 110 the latter to lift hook 177 as in Fig. 17. At the end of conversation the exchange calling plug is removed thus deenergizing relay X^1 which causes both armatures to drop whereby only spring 174 makes contact with hook 178 as by reason of hook 177 being raised spring 173 escapes contact therewith. 115

Current now flows from battery 44, the magnet of effectual call meter 17, line 186, hook 178, spring 174, line 187, contact 25 to 120 control relay 18 of calling subscribers call meter.

It will be seen that when armature 172 is released it permits bar 184 to descend and likewise hook 177 when both armatures engage the inclined portions 179 of the hooks raising same sufficiently to free the springs therefrom. 125

In the event of a wrong subscriber being called the relay X^1 is set as described to 130

register an effectual call, but when "A" ascertains the mistake, the operator's attention is called to the fact, when upon the calling plug being extracted to be correctly inserted in the required jack no call is registered on the meters because the registering circuit is broken at contact 25 for the reason that relay 24 while A's receiver is off the hook is energized and is attracting its 10 armature.

I claim:—

1. In telephone systems, an effectual call meter, an ineffectual call meter, a circuit for each meter, a relay in each circuit, a control 15 relay having two armatures respectively controlling the circuits of the said two relays, said armatures being so arranged that one requires a greater strength of current to operate it than the other, and means on the 20 control relay controlled by the armatures for completing one or the other of said relay circuits according as to whether the call is effectual or ineffectual.

2. A telephone system in accordance with 25 claim 1 characterized by an answering plug supervisory relay, an armature in the circuit of the effectual call meter operated by the answering plug supervisory relay to break the circuit of the effectual call meter 30 when the telephone circuit has been opened, subsequent to the connection of the telephone circuit with a wrong answering station.

3. In telephone systems, a calling plug, an 35 answering plug, an effectual call meter, an ineffectual call meter, an operative relay for each meter, a circuit for each relay and a control relay in the circuit of said plugs, said control relay being provided with two 40 armatures adapted to close one or the other of said relay circuits.

4. A telephone system in accordance with 45 claim 3, comprising an answering plug supervisory relay and an armature in the circuit of the effectual call meter operated by the answering plug supervisory relay to open the circuit of the relay of the effectual

call meter when the answering plug is removed after the wrong subscriber has been connected.

50

5. A telephone system in accordance with claim 3, characterized by the fact that it requires a greater current to operate one armature than the other.

6. In telephone systems, an effectual call 55 meter, an ineffectual call meter, means operative by the breaking of the line connection after an effectual call and after the calling subscriber has placed the receiver on the hook, for operating the effectual call meter, and means for operating the ineffectual call meter.

7. In telephone systems, an effectual call 60 meter, an ineffectual call meter, means operative by making of the outgoing connection 65 for setting the effectual call meter operating mechanism, means operative by the breaking of the line after the calling subscriber has placed the receiver on the hook, for operating the effectual call meter operating mechanism, and means operative on the breaking 70 of the circuit when the call subscriber has not answered for operating the ineffectual call meter.

8. In telephone systems, a calling subscriber station, a central station, a called subscriber station, means at the calling subscriber station for recording an effectual call on the called subscriber station, means at the central station for recording said effectual 75 call, and means at the central station for recording an ineffectual call on the called subscriber station.

9. In telephone systems, the combination 80 with entering subscriber's lines, of an effectual call meter and an ineffectual call meter, and means operative by the breaking of the circuit after the call has been made for operating one of said meters, the operation of the meter being controlled by the answering 85 or non-answering of the called subscriber.

Dated this 20th day of March, 1917.

WILLIAM JOHN BLAIR.
